UNITED STATES PATENT OFFICE.

ODILON ARCHAMBAULT, OF ST. HYACINTHE, CANADA.

ACETYLENE-GAS GENERATOR.

SPECIFICATION forming part of Letters Patent No. 626,477, dated June 6, 1899.

Application filed January 3, 1899. Serial No. 700,920. (No model.)

To all whom it may concern:

Be it known that I, ODILON ARCHAMBAULT, a subject of Her Majesty the Queen of Great Britain, residing at St. Hyacinthe, county of St. Hyacinthe, Province of Quebec, Canada, have invented certain new and useful Improvements in Acetylene-Gas Generators; and I do hereby declare the following to be a full, clear, and exact description of the invention, such as will enable others skilled in the art to which it appertains to make and use the same.

My invention relates to improvements in acetylene-gas-generating apparatus.

15 The object of my invention is to provide a construction in which a series of carbid-receptacles are operatively connected to the generating-chamber, each of said receptacles being adapted to be brought into operative 20 connection independently to enable the refilling when necessary.

A further object is to provide a construction simple and efficient which will automatically deliver the carbid to the generating-chamber.

25 A further object is to provide a generating-chamber in which the residue can be readily removed.

A further object is to provide a construction compact in form, simple and efficient in 30 operation, durable in construction, and which can be made at a moderate cost.

To these and other ends my invention consists in the improved construction and combination of parts hereinafter fully described, and particularly pointed out in the appended 35 claims.

In the drawings, in which similar numerals of reference indicate similar parts in all of 40 the views, Figure 1 is a perspective view of an apparatus constructed in accordance with my invention. Fig. 2 is a side elevation of the same. Fig. 3 is an elevation, partly in section, of the generator. Fig. 4 is a central vertical longitudinal sectional view of my apparatus. Fig. 5 is a horizontal sectional view of the gasometer.

1 designates the generator, formed substantially as shown and having the generating-chamber 2. The generating-chamber 2 is 50 provided with a supplemental bottom 3, cor-

rugated, as at 4, and arranged inclined, as best shown in Fig. 3. The top 5 of the generating-chamber is provided with a series of openings 6, in which are secured vertically-extending pipes 7, each of said pipes being provided with two valves 8 9, preferably arranged as shown in the drawings, said valves serving to regulate the passage of the carbid from the carbid-receptacle 10, as hereinafter described. As shown, each receptacle 10 is provided with an opening 11 at its top, to close which a removable cap 12 is provided, the opening 11 being adapted to allow of the passage of the carbid into the receptacle 10 during refilling. Each valve 8 is provided with an elongated stem 13, on which is mounted a tube 14, forming a lever by means of which the valve may be turned. A second lever 15, having a hook portion 16, is also mounted on the stem 13, said lever being extended in a direction opposite that of the lever or tube 14, the hook portion 16 being adapted to receive a weight 17, by means of which the valve will be normally held in its closed position. 70 The tube or lever 14 is adapted to receive one end of a removable rod 18, the opposite end of which is adapted to be removably connected to a rod 19, connected to and extending upwardly from the telescoping section 20 of the gasometer 21, the connection between the rod 18 and rod 19 being arranged to allow of a ready insertion of the end of the rod 18 into either one of the tubes or levers 14, the tube or lever 14 not operatively connected to 75 the rod 18 resting in a suitable supporting-hook 22, formed on the receptacle 10. The end of the rod 18 is bifurcated, as shown in Fig. 1, said end being adapted to embrace the rod 19, being held from vertical movement on said rod by means of suitable pins located in the rod 19 above and below the bifurcated end.

The valves 9 are provided with upwardly-extending levers 23 24, which are connected by means of a connecting-bar 25, the levers 23 and 24 being provided with suitable openings, by means of which the connecting-bar may be adjustably connected to the levers. The lever 24 is provided with an angular portion 26, having a handle 26^a, by means of which the valves 9 can be readily turned, the

connecting-bar 25 serving to cause the two valves to have a simultaneous movement, the valves being arranged in such manner that one valve will be closed when the other is open.

27 designates a pipe having connection with a source of water-supply, such as a hydrant, the lower end of said pipe entering the generating-chamber at a point a short distance above the central corrugation, a branch pipe 28 being provided for each of the remaining corrugations, said pipes entering the generating-chamber practically on the same horizontal plane. The opposite side of the generator is provided with a pipe 29, having a connection with a point outside of the building, preferably the sewer, said pipe being connected to the generating-chamber by means of short connections 30, one being provided for each corrugation, the connections 30 entering the chamber at the lowest point of the corrugations. Suitable valves are placed in the pipes 27 and 29, by means of which they may be brought into and out of operation, as may be desired. The generator is also provided with a tube 31, by means of which the depth of water in the generator may be readily determined.

The gasometer 21 is provided with a U-shaped frame 32, which serves as a guide for the telescoping section, the rollers 33, located on the section 20, operating against the frame 32, as shown in Fig. 1, and also serving as a stop to limit the upward movement of said section. The rod 19 is adapted to pass through an opening formed in the frame 32, thus insuring a true vertical movement of said rod.

The generating-chamber is connected to the gasometer by means of the pipe 34, the pipe 40 passing into the gasometer above the water-line in the usual manner. A pipe 35, extending into the gasometer, serves as a conduit for the gas from the gasometer to the service-pipes. A pipe 36, connected to the gasometer 45 and extending therein near its bottom, serves as an outlet for the water therein when it is desired to empty the gasometer, a suitable valve being provided to control said outlet.

A safety device consisting of the pipe 37, connected to the stationary section 38 and leading to the outer atmosphere, as shown in Fig. 5, over which the pipe 39, secured to the section 20, is adapted to move, the arrangement being such that should the section 20 pass to a height greater than desired the seal between the pipes 37 and 39 will be broken and the surplus gas will pass out through the pipe 37, thus preventing any liability of a dangerous explosion.

60 To allow of an access to the interior of the generating-chamber, I provide a suitable hand-hole 40, having a cap 41, while to allow of the escape of the air when the generator is first placed in operative position I provide a pipe 42, having valve 43.

It will be readily seen that as the section 20

of the gasometer moves vertically the valve 8, operatively connected therewith, will be given a movement to open and close the valved opening, allowing the carbide to pass downward 70 through the pipe and valve 9 to the generating-chamber. As before explained, the valves 8 are arranged to be opened alternately, as desired. By this construction the carbide-receptacle not in use can be detached for filling, 75 if desired, yet preventing the outlet of gas when the receptacle is removed.

By reason of the corrugated bottom channels will be formed within which the residue falls, from which it can be readily removed 80 by opening the pipes 27 and 29, the water passing through the channels and forcing the residue therefrom.

A suitable trap may be provided in the pipe 35, by means of which the water of condensation will be taken from the gas automatically.

The advantages of this construction are obvious and it is not thought necessary to point them out in detail.

While I have herein shown a preferred form of carrying my invention into effect, yet I do not desire to limit myself to such preferred details of construction, but claim the right to use any and all modifications thereof which 95 will serve to carry into effect the objects to be attained by this invention in so far as such modifications and changes may fall within the spirit and scope of my said invention.

Having thus described my invention, what 100 I claim as new is—

1. The combination with an acetylene-gas generator, of a plurality of carbide-receptacles operatively connected therewith, said receptacles being adapted to be operated alternately; and a series of valves located in the connections between the receptacle and the carbide-chamber, the lower valve in each connection being connected to a common actuating means, the remaining valves having independent movement, substantially as described.

2. An acetylene-gas generator, comprising a generating-chamber; a supplementary bottom formed therein, said bottom being provided with inclined channels, adapted to receive the residue; means for forcing a stream of water through each of said channels; means for delivering carbide to said chamber at predetermined periods; and connections between 115 the generating-chamber and the service-pipes, substantially as described.

3. An acetylene-gas generating apparatus, comprising a generating-chamber, having an inclined corrugated bottom; a series of carbide-receptacles operatively connected thereto, said receptacles being brought into operation alternately; a gasometer; connections between the generating-chamber and the gasometer for the passage of the generated 125 gas; connections between the gasometer and the carbide-receptacle for regulating the pas-

sage of the carbid into the generating-chamber; a gas-outlet formed in the gasometer; a surplus gas-escape pipe located in said gasometer; and a series of pipes connected to the water-supply, adapted to force water along said corrugated bottom, whereby the residue will be carried off, substantially as described.

In witness whereof I have hereunto set my hand in the presence of two witnesses.

ODILON ARCHIAMBault.
